No. 653,201.

Patented July 10, 1900.

Z. C. ANGEVINE.
LIFE PRESERVER.

(Application filed Oct. 21, 1899.)

(No Model.)

UNITED STATES PATENT OFFICE.

ZENUS C. ANGEVINE, OF NEW YORK, N. Y.

LIFE-PRESERVER.

SPECIFICATION forming part of Letters Patent No. 653,201, dated July 10, 1900.

Application filed October 21, 1899. Serial No. 734,321. (No model.)

To all whom it may concern:

Be it known that I, ZENUS C. ANGEVINE, of the city of New York, borough of Brooklyn, in the county of Kings and State of New York, have invented a new and Improved Life-Preserver, of which the following is a full, clear, and exact description.

This invention relates to improvements in life-preservers in the form of a jacket; and the object is to provide a life preserver or jacket having not only means for keeping a person afloat in the water, but having receptacles for holding food and drink, signaling devices, and implements.

I will describe a life-preserver embodying my invention and then point out the novel features in the appended claims.

Reference is to be had to the accompanying drawings, forming a part of this specification, in which similar characters of reference indicate corresponding parts in all the figures.

Figure 1 is a plan view of a life-preserver embodying my invention. Fig. 2 is a section on the line 2 2 of Fig. 1. Fig. 3 shows the device as applied; and Fig. 4 is a section through one of the air bags or containers, showing the position of the same when a person is floating.

Referring to the drawings, 1 designates a jacket of any suitable material—such, for instance, as canvas or other material preferably made impervious to water. The jacket has fastening devices, here shown as hooks 2 at one edge, adapted to engage with opposite rings or any one of the opposite rings 3, which are attached to straps 4, so that the jacket may be adjusted to the size of the wearer.

Attached to the lower edge at the back of the jacket are straps 5, adapted to pass between the legs of the wearer and to engage, by means of their hooks 6, with a ring 7, attached to the front portion of the jacket, several of these rings being arranged in a row for the purpose of adjustment. Attached to the front portion of the jacket at each side is an air container or receptacle 8, provided with a valve 9, through which the bags or receptacles may be inflated or deflated.

Extended up the back of the jacket substantially in line with the shoulders are air bags or containers 10, adapted to be inflated or deflated through valves 11. These bags

or containers 10 are shown as oval in cross-section and attached at their inner sides to the material of the jacket in such manner that they may be drawn laterally, as indicated in Fig. 4, to present a wider surface to rest upon the water, which will materially aid a person to float by lying upon his back in the water. As a means for drawing the bags or receptacles 10 laterally or outward toward the arms, I employ cords 12, which are attached to said bags or receptacles and pass through guides 13, attached to the jacket, and pass around to the front, where they may be tied together to hold said bags or receptacles in their adjusted position.

Extended up along the back of the jacket is a pocket or receptacle 14 for containing a day-signal—such, for instance, as a flag or flags—which pocket is provided at its upper end with a suitable cover, as indicated in the drawings. For the purpose of night signaling rockets are employed. These rockets are carried in pockets 15, secured to the jacket at the shoulder portions, and these pockets, of course, will be provided with water-tight covers. I have shown two rocket-pockets on each shoulder of the jacket; but it is obvious that more or less may be employed without departing from the spirit of my invention.

Attached to the jacket, here shown as underneath one of the arm-holes, is a pocket 16 for holding a gun or discharging device 17 for propelling a rocket into the air, and attached to the jacket underneath the opposite arm-hole is a sheath 18 for a knife 19.

Attached to the back of the jacket at opposite sides of the pocket 14 are liquid receptacles 20 and 21, one of which may contain water and the other contain whisky or other stimulant. From the receptacles 20 and 21 tubes 22 23 extend through the upper portion of the jacket and are provided with mouthpieces 24 25, which may be provided with suitable valves to prevent water flowing into the same.

A food receptacle or can 26 is provided with a water-tight cover, and as a means for attaching it to the jacket I provide the receptacle or can with a hook or strap 27, adapted to engage in staples 28, attached to the jacket. It is also secured to the jacket by means of a line or cable 29, attached at one end to the

can and at the other end to a ring 30 upon the jacket. By this arrangement it is obvious that there will be no danger of losing the can should it be dropped from the hand after removing it from connection with the staples 28. When the can is supported by the staples 28, the cord or cable 29 may be folded and held in a loop 31, attached to the jacket.

Having thus fully described my invention, I claim as new and desire to secure by Letters Patent—

1. A life-preserver, comprising a jacket, a food-receptacle, a hook on said receptacle, staples on the jacket for receiving said hook, a cord or the like connection between the receptacle and the jacket, and a loop on the

jacket for receiving the cord when folded, substantially as specified.

2. A life-preserver, comprising a jacket, supporting devices extended up the back thereof, one at each side of the center line, a signal-receiver extended along the center line of the back, liquid-holders on the jacket between said signal-receiver and the supporting devices signal-receivers on each shoulder portion of the jacket, and supporting devices at the front portion of the jacket, substantially as specified.

ZENUS C. ANGEVINE.
